UNITED STATES PATENT OFFICE.

OTTO P. DRIEBUSCH, OF MEDFORD, WISCONSIN.

LOCK.

1,105,632.

Specification of Letters Patent.

Patented Aug. 4, 1914.

Application filed June 3, 1912. Serial No. 701,330.

To all whom it may concern:

Be it known that I, OTTO P. DRIEBUSCH, a citizen of the United States, residing at Medford, in the county of Taylor and State of Wisconsin, have invented new and useful 5 Improvements in Locks, of which the following is a specification.

This invention relates to the class of locks, and more specifically to the class of locks 10 which are designed for use in connection with hasps, however, I desire it to be understood that the same can be advantageously employed in connection with other devices as well.

15 An object of this invention is to provide a lock which consists of but a few simple parts whereby it can be easily and cheaply manufactured, and one which is durable and efficient in operation.

20 With the above and other objects in view, my invention relates to such details of construction and in arrangement and combination of the several parts as will be herein-after fully described and specifically pointed 25 out in the appended claims.

In describing my invention in detail, reference will be had to the accompanying drawings wherein like characters denote like or corresponding parts throughout the several views, and in which,

30 Figure 1 is a front elevation of my improved lock as shown in actual use. Fig. 2 is a side elevation of the lock, showing a portion of the same removed. Fig. 3 is a similar view. Fig. 4 is a detailed view.

35 In the accompanying drawings wherein is illustrated the preferred form of my invention, the numeral 1 designates an ordinary hasp which has a bracket 2 secured thereon, 40 which bracket has pivotal connection with the link 3. A slot 4 is provided in the hasp through which slot projects a staple 5 for the purpose obvious.

45 My invention comprehends casing sections 6, which have off-set portions 7 formed thereon and provided with openings 8 for the reception of suitable fastening members. Slots 9 are provided in each of the sections, which slots extend vertically in relation 50 thereto and have operating thereon pins 10, which are carried by a member 11, the said member having its lower end constricted as shown at 12, to form shoulders which provide cam surfaces for the purpose that will 55 be hereinafter set forth. For purpose of securing the substantial semi-circular shackle

members 13, links 14 are provided upon the member 11 and have pivotal connection with the latch member as shown. It is obvious that when the ends of the shackle means are 60 brought together through the staple 5 and the member 11 forced downwardly that the device will be locked and cannot be opened without the use of a key. The key (shown by dotted lines in Fig. 2) is inserted in the 65 keyhole 15 formed in one of the casing members and turned to raise the member 11, thereby throwing the shackle member out of engagement with each other.

The greatest of stress is laid upon the simplicity of my invention, and it is thought that the advantages and novel features of the same will be readily appreciated from the foregoing disclosure.

I desire it to be understood that I may 75 make slight changes in the construction and in the arrangement and combination of the several parts, provided such changes fall within the scope of the sub-joined claims.

Having thus fully described my invention 80 what I claim is new and desire to secure by Letters Patent is:—

1. In a device of the character described, a lock comprising casing sections secured together, a member slidably mounted upon one 85 of said casing sections, an extension formed upon said member and projecting downwardly therefrom and shackle members pivotally secured to said member for the purpose described.

90 2. In a device of the character described a lock comprising casing sections rigidly secured together, a member slidably mounted upon one of said casing sections, links carried by said member, shackle members pivotally secured to said links, an extension depending from said first mentioned member, whereby said latch members may be closed for the purpose described.

95 3. In a device of the character described, a lock comprising casing sections rigidly secured together, one of said casing sections provided with spaced apart longitudinally extending slots, a member having pins inserted therethrough, said pins adapted to engage in said slots whereby said member is held in slidable engagement thereto, links carried by said member, shackle members pivotally secured to said links, and an extension depending from said first mentioned member for the purpose described.

100 4. In a device of the character described, a

lock comprising casing sections, one of said casing sections provided with slots, a member having cam surfaces formed on the opposite sides thereof, pins journaled in said member and projecting into said slots to hold said member in slidable relation to the casing sections, links carried by said member, shackle members secured to said links and having portions adapted to engage said cam surfaces so as to move said latch members into and out of engagement for the purpose set forth.

5. In a device of the character described, a lock comprising sections rigidly secured together, each of said members provided with a plurality of openings for reception of fastening means whereby they may be held to-

gether, one of said sections provided with spaced apart longitudinally extending slots, a member having pins projecting therefrom, 20 said pins projecting into said slots whereby said member is held in slidable engagement with said sections, an extension depending from said member, links carried by said member, substantial semi-circular latch 25 members carried by said links and means for lowering and raising said members so as to move the upper ends of said latch members into and out of engagement with each other for the purpose described.

OTTO P. DRIEBUSCH.
